VOTING MACHINE

Alvin N. Gustavson, Jamestown, N. Y., assignor
to Automatic Voting Machine Corporation, a
corporation of Delaware

Application June 5, 1937, Serial No. 146,642

1 Claim. (Cl. 235—51)

This invention relates to an improvement in a voting machine, and particularly to means adapted to prevent use of any portion of the machine not required in a given candidate set up. It frequently occurs in small communities, and on occasion in larger communities, that an entire voting machine is not required for use with a given candidate set up. The unrequired indicators on the face of the machine are locked against manipulation or are disconnected from any active part of the mechanism. Due to the fact that it is desirable for voters to indicate and record their ballots promptly, confusion has sometimes occurred and resulted in voters casting improper or invalid ballots because only certain of the indicators on the face of the machine were intended to be manipulated and certain others were either locked against manipulation or were obviously disconnected from the mechanism. In view of this objectionable set up, shields were provided for the purpose of concealing the unrequired indicators. These shields were intended to merely cover the indicators and little or no effort was made to lock them in place. It soon became evident that shields were also objectionable, not from the standpoint of confusion to the voter, but rather because unscrupulous or curious voters attempted to pry them off and manipulate indicators located therebeneath. In some instances it is possible to secure one or more shields against unauthorized removal, but for the most part these shields are attached to a ballot label holder, and therefore, at best, merely serve as a means of concealing the indicators and are not intended to be proof against forced removal.

The present invention is directed to a structure adapted to eliminate the objectionable features of exposed and shielded unrequired indicators through the use of candidate indicators that are removably connected with the mechanism of which they form a part. Each indicator when removed, leaves an opening in the face of the machine that is closed by a small button. This button is locked in place and not only cannot be removed but also locks the particular indicator mechanism against movement.

One of the objects of the invention lies in the provision of voting machine indicators that are removable from the face of the machine.

Another object of the invention lies in the provision of a voting machine equipped with removable indicators for which suitable buttons may be substituted.

Another object of the invention lies in the provision of substitute buttons for removed indicators

which lock the individual indicator mechanism they supplant against operation.

Other and further objects of the invention will be more apparent from a consideration of the following specification taken in conjunction with the accompanying drawing and in which

Fig. 1 is a fragmentary front elevation of a portion of the face of a voting machine showing one modification of the invention;

Fig. 2 is a plan view of the structure shown in Fig. 1;

Fig. 3 is a rear view of a portion of the structure shown in Figures 1 and 2;

Fig. 4 is an enlarged cross sectional view of the mounting of an indicator, being taken substantially on the line 4—4 of Figure 1;

Fig. 5 is a perspective view of one of the candidate indicators;

Fig. 6 is a perspective view of a button adapted to be substituted for a candidate indicator;

Fig. 7 is a view of the structure which serves to lock the indicators and buttons against removal, being in a position to permit removal or insertion of either indicator or button; and

Fig. 8 is a further view of indicator locking mechanism, being shown in locked position.

Referring to the drawing, the reference numeral 10 is employed to designate a portion of the front plate of a voting machine embodying the invention. Mounted on a voting machine of this type are a number of horizontally disposed ballot holders 11. Directly above each holder 11 is a horizontal row of candidate indicators 12.

Spaced slightly from the plate 10 is a further plate 13. This plate is adapted to mount studs 14, of which there is one for each indicator 12. The plate 13 is provided with suitable openings 15 through which the studs 14 project. Each stud is formed with an annular head 17, in the outer face of which is a slot 18. The stud is formed with a reduced diameter portion 19 which is threaded at its outer end to receive a nut 20, that may be held against displacement by a lock washer 21. That portion of the stud 14 which lies in the opening 15 of the plate 13 is of greater diameter than the portion 19, and a shoulder 22 is thus formed. Mounted on the portion 19 and held in abutment with the shoulder 22 by the nut 20 is a U-shaped member 24 which is adapted to be connected with interlocking straps (not shown). The member 24 (see Fig. 3) is formed with a lug 25 which lies adjacent the rear of the plate 13 and is adapted to be contacted by a primary bar 27. The bar 27 is supported in any suitable manner, as by pins which are mounted on plate 13 and

50
55

project through slots in the bar. The bar may be laterally moved for the purpose of resetting the indicators.

The front plate 10 is arranged with horizontal rows of keyhole openings 30. These openings are so disposed that the narrow portion 31 thereof is in a horizontal position. Located adjacent the rear face of the plate 10 are locking bars 32. These bars are provided, one for each row of indicators. The bars are formed with several slots 33 through which pins 34 project. Formed in the bar is a plurality of horizontally disposed keyhole openings 35. The narrow portion 36 of each of these openings is approximately twice 15 the width of the corresponding portion 31 of the keyhole opening in the plate 10.

The indicator 12, as clearly shown in Figures 2, 4, and 5, consists of an arm 38 which is joined to or made integral with a stud 39. A finger piece 40 is secured to the free end of the arm 38. The stud 39 is formed with an annular shoulder 42 from which a reduced diameter portion 43 continues. In the portion 43 is an annular groove 44. At the end of the portion 43 a lug 25 46 is fitted which, being longer than the diameter of the portion 43, extends therebeyond.

Figure 6 shows a replacement button 48, which is formed with an annular shoulder 49 and a reduced diameter portion 50. Formed in the portion 50 is a groove 51, the base wall of which has two diametrically opposite flat surfaces 52. At the end of the portion 50 is a lug 53. It will be noted that, with the exception of the difference in size of the lug 53, the contour of the base wall 52 of the groove 51, and the fact that there is no arm on the button, said button is substantially identical with the indicator 12.

Attention is now directed to the installation of an indicator on the machine and connection 40 thereof with the voting mechanism. The locking bar 32 is moved laterally to cause the keyhole openings 35 therein to register with the keyhole opening 30 of the front plate 10. The lug 46 and portion 43 of the indicator may now be projected through the two keyhole openings 30 and 35 and the indicator rotated downwardly until the projecting edge of the lug fits into the slot 18 of the stud 17. The indicator is now connected with the arm 24 and the remainder of 45 the voting machine mechanism. It will be noted that the lug 46 projects into a slot provided therefor in a straight ticket bar 55, which is mounted against the front face of the rear plate 13 and is laterally movable due to provision of 50 horizontal slots through which supporting pins project. The indicator now being in place, the locking bar 32 is moved laterally in the opposite direction and the side walls of the reduced portion 36 of the keyhole opening 35 move into 55 the annular groove 44. Thus the indicator is prevented disengagement with the stud 17, which

as heretofore brought out, is connected with the indicator mechanism.

When candidate ballot strips have been inserted in the holders 11 and the interlocking mechanisms of the voting machine have been 5 arranged for the desired voting set up, those indicators not required may be removed by simply releasing the locking bar 32, withdrawing the indicators 12 from engagement with studs 17, rotating them so that the lugs 46 register 10 with the keyhole openings 30 and 35 and completely removing them. For each indicator 12 that is removed a button 48 may be substituted. This button is projected through the keyhole openings 30 and 35 and rotated so that the lug 15 53 thereof enters the slot 18 of the stud 17. The locking bar is then adjusted and the side walls of the reduced portion 36 of the keyhole opening 35 engage opposite flat surfaces 52 of groove 51. Thus, the plug cannot be rotated, and since 20 the lug 53 engages stud 17, no part of the mechanism previously connected with the removed indicator can deliberately or by accident be moved out of non-voting position.

It will be understood that the locking bars 32 25 are concealed by the front plate 10 of the voting machine and are not, therefore, accessible to the voter but must be adjusted at the time the voting machine is set up for a given election. Thus, when a voter casts his ballot on a voting 30 machine equipped with the structure above described, he will find that there is an indicator for each candidate or question and the remainder of the machine will be without indicators and in place thereof only the buttons 48 will be 35 visible. Inasmuch as it is impossible for a voter to either rotate or remove these buttons, he has no choice but to actuate the indicators of the machine in their intended manner.

Although applicant has shown and described 40 only one modification of the invention, it will be apparent to those skilled in the art that other modifications or adaptations may be made without departing from the spirit and scope of the invention as defined in the hereunto annexed 45 claim.

Having thus set forth my invention what I claim as new for which I desire protection by Letters Patent is:

In a voting machine, a front plate, said plate 50 having an opening, a stud located to the rear of said plate and adjacent said opening, said stud being connected with an interlocking and registering mechanism of said machine, a button on said plate, said button having a portion 55 projecting through said opening and being engageable with said stud when said stud is in non-actuated position, and means adapted to secure said button against rotation and disengagement from said stud.

ALVIN N. GUSTAVSON.
